COOKING RANGE CONSTRUCTION

Robert J. Merritt, Los Angeles, Calif.

Application June 18, 1937, Serial No. 148,872

9 Claims. (Cl. 126—333)

This invention relates to cooking stoves or ranges and it is a general object of the invention to provide a stove or range of improved design and construction.

5 Modern cooking ranges for domestic use often have hinged covers for covering the top burners and the plate warming top of the oven when the range is not in use. Brackets or pockets are often provided on the rear guard rail of such 10 ranges to carry condiment vessels, flour containers, etc. It is the usual practice to hinge the burner cover and oven cover at their rear edges and when the covers are raised, to make the top burners and oven top accessible for use, 15 they conceal and make the condiment pockets inaccessible so that the condiment pockets are of no actual benefit when the range is in use.

Another object of this invention is to provide a cooking range structure having a top burner 20 cover and a condiment carrier in which the parts are so related that the condiment carrier is conveniently accessible when the burner cover is raised.

Another object of this invention is to provide 25 a cooking range embodying a condiment carrier that may be readily moved from its normal position at the rear guard rail to a conveniently accessible position where it will not be concealed or made inaccessible when the burner cover is raised.

30 Another object of this invention is to provide a cooking range construction of the character mentioned in which the condiment carrier may be normally received in a pocket in the rear guard rail to constitute an attractive fixture or adjunct 35 to the range.

Another object of this invention is to provide a range construction of the character mentioned in which the condiment carriers never strike or interfere with the oven cover or burner cover.

40 Another object of this invention is to provide a cooking range construction of the character mentioned in which the condiment carriers and their supports may be inexpensively embodied in the range construction with little or no alteration 45 of the guard rail or other parts.

A further object of this invention is to provide a cooking range construction of the character mentioned in which the condiment carriers are disposed adjacent the ends of the range when 50 moved to their extended positions, so that the range does not require excessive room space.

The various objects and features of my invention will be fully understood from the following 55 detailed description of typical preferred forms and applications of the invention, throughout

which description reference is made to the accompanying drawings, in which:

Fig. 1 is a fragmentary front elevation of a range embodying one form of the invention showing the covers closed and the condiment carriers 5 in their normal or retracted positions. Fig. 2 is an enlarged fragmentary horizontal detailed sectional view taken substantially as indicated by line 2—2 on Fig. 1 with the condiment containers removed from the carrier. Fig. 3 is an enlarged 10 vertical detailed sectional view taken as indicated by line 3—3 on Fig. 2. Fig. 4 is a fragmentary horizontal detailed sectional view taken as indicated by line 4—4 on Fig. 3. Fig. 5 is a fragmentary front elevation similar to Fig. 1 illustrating one of the covers in its raised position and showing a condiment carrier in its out or accessible position. Fig. 6 is a fragmentary front elevation of the upper portion of a range illustrating another form of the invention. Fig. 7 is an enlarged fragmentary horizontal detailed sectional view taken as indicated by line 7—7 on Fig. 6 and illustrating the carrier in broken lines in the extended position. Fig. 8 is an enlarged vertical 20 detailed sectional view taken as indicated by line 8—8 on Fig. 6 and Fig. 9 is a view similar to Fig. 7 illustrating another form of the invention.

The present invention may be embodied in cooking ranges of various styles and makes and in gas ranges as well as electric ranges. In the 30 following detailed description I will describe several typical embodiments of the invention, it being understood that the invention may be varied considerably to adapt it for use on different types and styles of ranges.

The range construction illustrated in Figs. 1 to 5, inclusive, includes, generally, the range body 10, a guard rail 11 extending along the upper rear edge of the body 10, hinged covers 12 movable from down positions over the top of the range 40 body 10 and open vertical positions adjacent the rail 11, and shiftable condiment carriers 13 movable from positions at the ends of the rail clear of the tops 12.

The stove or range body 10 may be of any conventional or desired shape and construction. The present invention is not primarily concerned with the construction of the range body 10 and I have illustrated only a portion of a more or less typical range body 10 having a flat horizontal top. One 50 half of the upper portion of the range body 10 may be considered as the upper end of an oven while it may be considered that the usual top burners are located on the top of the other half of the body 10.

The guard apron or rail 11 may be a substantially vertical member extending along the rear edge of the top of the body 10. The rail 11 may be formed of enameled sheet metal and may have a distinctive or ornamental outline as illustrated. Horizontally spaced openings 14 may be provided in the inner or central portion of the rail 11 to receive an automatic burner control clock and a cooking chart or the like. In accordance with 10 the form of the invention illustrated in Figs. 1 to 5 the rail 11 has recesses or pockets 15 for receiving the condiment carriers 13. Where the range has two carriers 13, as illustrated, there are two pockets 15 provided in the rail 11. The 15 pockets 15 are spaced inwardly from the opposite ends of the rail 11 and are suitably spaced between the upper and lower edges of the rail. In the particular construction illustrated the pockets 15 are substantially rectangular and have rectangular fronts or mouths. The pockets 15 may be defined by suitable members 16 of enameled sheet metal, or the like. The members 16 are secured to the rear side of the rail 11 by brackets 17 and project rearwardly from the rail so that 20 the pockets 15 extend inwardly or rearwardly from the front surface of the rail. The pocket members 16 are, of course, shaped or formed to give the pockets 15 the desired configuration.

The covers 12 are provided to extend over the 30 top range burners (not shown) and the upper wall or plate warming top of the range oven. The covers 12 may be of any suitable construction and may have any desired finish. In practice the covers 12 may be substantially rectangular and 35 may be relatively thin, it being understood that the covers 12 may be hollow to contain suitable insulation. The covers 12 normally lie flat and horizontal at the top or upper side of the range body 10. In accordance with the usual practice 40 the covers 12 are hinged to the body 10 at their rear edges so that they may be swung upwardly and rearwardly to substantially vertical positions where they are adjacent and substantially parallel with the rear rail 11, as illustrated in Fig. 5. 45 It will be apparent that when a cover 12 is in the position illustrated in Fig. 5 it closes and conceals one of the pockets 15, rendering it inaccessible. Further, it will be noted that the top burners or the plate warming top of the oven, as the case 50 may be, cannot be used or made accessible without first raising a cover 12 to the vertical or raised position shown in Fig. 5.

The carriers 13 are provided to contain receptacles 18 for containing condiments, flour, sugar, 55 and the like, or may be employed to carry any objects or devices that may be useful about the range. It is an outstanding feature of the invention that the carriers 13 may be moved or shifted between positions in the pockets 14 and 60 positions at or beyond the outer ends of the guard rail 11. The carriers 13 are shaped and proportioned to be readily received in the pockets 15 and to carry the condiment receptacles 18 or the like. In accordance with the broader aspects 65 of the invention the carriers 13 may be of any suitable shape and construction. In the particular case illustrated the carriers 13 are substantially rectangular open topped basket-like elements.

70 Each carrier 13 may comprise two or more substantially horizontal rods 19 spaced apart vertically and shaped or bent to constitute the sides and the ends of the carriers. The rods 19 may be continuous and in the construction illustrated 75 project or continue horizontally from the front

sides of the carriers 13 toward the adjacent ends of the rail 11, assuming the carriers 13 to be in their normal positions in the pockets 15. Thus the carriers 13 project laterally or rearwardly from the inner ends of the horizontal rods 19. 5 In the simple construction illustrated the rods 19, which constitute the sides and ends of the carriers 13, also serve as supporting arms for the carriers, as will be subsequently described. Spaced straps 20 extend across the lower ends of the carriers 13 and are secured to the rods 19 at the opposite ends of the carriers to constitute the bottoms of the carriers. The straps 20 serve to support the condiment receptacles 18 in the carriers 13. In the preferred arrangement the carriers 3 are arranged and proportioned to fit in the lower portions of the pockets 15 so that the condiment receptacles 18 may project upwardly from the carriers within the pockets to be conveniently accessible for removal from the pockets. This 20 construction also renders the receptacles 18 conveniently accessible for removal from the carriers 13 when the carriers are in their extended positions remote from the pockets 15. The carriers 13 and their supporting rods 19 may be suitably 25 plated or finished to constitute decorative or ornamental attachments or parts of the range.

In accordance with the form of the invention illustrated in Fig. 5 of the drawings the condiment carriers 13 are pivotally or swingably supported to swing horizontally between positions in the pockets 15 and positions at or beyond the ends of the rail 11 where the receptacles 18 are accessible when the tops 12 are raised. The outer end portions 21 of the carrier rods 19 are bent 30 to curve around the ends of the rail 11 to the rear of the rail when the carriers 13 are in their normal positions in the pockets 15. The outer ends of the curved rods 19 are swingably or pivotally secured to the range body structure. In the particular arrangement illustrated brackets 22 are secured to posts 9 of the range construction at the rear of the rail 11 adjacent the ends of the rail. Each bracket 22 has vertically spaced rearwardly extending bearing projections 23 and 24. The 40 ends of each pair or set of carrier rods 19 are fixed to substantially vertical pintle pins 25 which are pivotally carried by the bearing projections 23 and 24 of the brackets 22. The rods 19 may be welded or otherwise fixed to the pintle pins 25. 50 The lower portions of the pins 25 are turnably supported in openings 26 in the lower bearing projections 23 and the upper portions of the pins 25 are rotatably carried in openings 27 in the upper bearing projections 24. The lowermost 55 rods 19 may bear on the upper surfaces of the projections 23 to limit the downward movement of the pintle pins 25.

Lugs 28 project upwardly from the lower bearing projections 23 and are engageable by the lower rods 19 to limit the outward movement of the carriers 23. The lugs 28 are located to stop the carriers 13 in positions at or slightly beyond the outer ends of the rail 11. Fig. 5 illustrates one of the carriers 13 in its out position at the adjacent end of the rail 11. Stop lugs 31 may be provided on the upper sides of the bearing projections 23 to be engaged by the lower arms 19 to limit the inward swinging of the carriers 13. If 70 desired the rods 19 may also have bent portions 32 for engaging against the forward face of the rail 11 to limit the inward swinging of the carriers 13. The inward movement of the carriers 13 is preferably stopped so that the inner sides of the 75

carriers are spaced from the inner walls of the pockets 15, as illustrated in Fig. 2.

The invention preferably includes drag means or friction means for resisting movement of the carriers 13 so that the carriers remain in the selected or desired positions until deliberately shifted. The friction means may include glands 29 threaded in the upper portions of the openings 27 and packing 30 or other suitable material in the openings 27 compressed by the glands 29 to offer the desired resistance to turning of the pintle pins 25 in the openings 27. It is believed that it will be apparent how the glands 29 may be tightened down so that the packing 30 offers the desired resistance to movement of the carriers 13 whereby the carriers remain in the desired positions until deliberately shifted.

It is believed that the utility and practicability of the form of the invention illustrated in Figs. 1 to 5 of the drawings will be understood from the foregoing detailed description. When the covers 12 are in their down positions the condiment carriers 13 may be received in the pockets 15 as illustrated in Figs. 1 and 2. When the carriers 13 are in this position they add to the general appearance of the range and the condiment receptacles 18 are conveniently accessible. When it is desired to raise one of the covers 12 to expose the top range burners or the plate warming top of the oven for use, the adjacent carrier 13 may be swung outwardly to a position such as illustrated in Fig. 5. The stop lug 28 is adapted to limit the outward movement of the carrier 13 to position the carrier at the end of the rail 11 where its condiment receptacles 18 are convenient for use. It will be understood of course that where both covers 12 are to be raised both carriers 13 may be swung to their out positions to render them accessible. Following the outward swinging or movement of the carrier or carriers 13 as the case may be, the cover or covers 12 may be swung upwardly to their raised vertical positions.

Figs. 6, 7 and 8 of the drawings illustrate a form of the invention in which the pivotal axes 45 of the carriers 13^a are at the front of the guard rail 11. The carriers 13^a of the structure illustrated in Figs. 6 to 8 may be identical with the above-described carriers 13. The rods 19^a extending from the carriers 13^a project outwardly 50 toward the adjacent ends of the rail 11 and terminate some distance from the ends of the rail. The means for swingably supporting each carrier 13^a includes two vertically spaced bearing blocks 33 on the forward face of the rail 11. The blocks 33 may have studs 34 extending rearwardly 55 through openings 35 in the rail 11 and nuts 36 may be threaded on the studs 34 to secure the bearing blocks 33 to the rail. A vertical pintle pin 37 is welded or otherwise fixed to the outer ends of each set or pair of carrier rods 19^a. The pins 37 have their opposite end portions pivotally supported in vertical sockets 38 in the bearing blocks 33. The pintle pins 37 support the carriers 13^a for swinging movement about vertical axes.

The carriers 13^a are swingable between positions in the pockets 15 and positions at or adjacent the ends of the rail 11 to be accessible when the covers 12 are raised to their vertical positions. Fig. 7 of the drawings illustrates one of the carriers 13^a in its normal position in a pocket 15 in full lines and illustrates the carrier in its extended position in broken lines. The rods 19^a of the carriers 13^a are substantially parallel with the rail 11 when the carriers 13^a are in the pockets 75 15 so that the carriers do not interfere with the

covers 12 and are not engaged by the covers 12 when the same are raised. It is to be understood that the carriers 13 may be employed to contain the condiment receptacles 18 or any other objects that may be useful at the range.

Fig. 9 of the drawings illustrates still another modification of the embodiment of the invention illustrated in Figs. 1 to 5, inclusive, of the drawings. In the construction illustrated in Fig. 9 the rail 11^b of the range is substantially vertical 10 and is devoid of pockets for receiving the condiment carriers. The condiment carrier 13^b illustrated in Fig. 9 may be of substantially the same shape and construction as the above-described carriers 13^b except that it projects outwardly or 15 forwardly from its rods 19^b when in its normal position at the forward face of the rail 10^b. The carrier rods 19^b are similar to the above described rods 19 having curved end portions 21^b which extend around the adjacent end of the rail 11^b 20 when the carrier 13 is in its normal position at the front of the rail. The outer ends of the carrier rods 19^b may be supported for swinging movement about a vertical axis by a bearing means 40 which may be identical with the means for supporting a carrier 13 as described above. The carrier rods 19^b may have rearwardly bent portions 32^b for contacting the rail 11^b to position the carrier 13^b at the face of the rail.

It is believed that it will be understood how 30 the carrier 13^b may be swung from the normal position illustrated in Fig. 9 to an extended position adjacent the end of the range to allow the adjacent cover 12 to be swung upwardly to its vertical position. When the carrier 13^b is in its extended position at the end of the range body 10 35 it is conveniently accessible and does not in any way interfere with the use of the range burners or the movement of the cover 12.

My co-pending application Ser. No. 148,871, filed June 8, 1937, now Patent No. 2,125,514, granted August 2, 1938, discloses and claims a construction in which a condiment carrier is movable between an accessible position beyond an end of the cooking range and a position at the rear of the rail where it is accessible through an opening in the rail.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. In a cooking range construction, a guard rail having an opening, a condiment carrier, and means supporting the carrier for movement between a position in the opening and a position adjacent an end of the rail.
2. In a cooking range having a rear guard rail with an opening and a cover hinged to be opened to a substantially vertical position in front of the rail, a condiment carrier, and means for swinging the carrier about a substantially vertical axis between a position where its contents are accessible through the opening and a position where it will be accessible following the opening of the cover.
3. A cooking range construction for a range body comprising, a guard rail for the body having a pocket open at its face, a condiment carrier, and a pivoted member supporting the carrier for movement between a position in the pocket and a position at one side of the body.

4. A cooking range construction for a range body comprising, a guard rail for the body having a pocket open at its face, a condiment carrier, a supporting member for the carrier, and means at the rear of the rail mounting the member for swinging movement whereby the carrier is movable from a position in the pocket to a position at a side of the body. 5
5. A cooking range construction for a range body comprising, a guard rail for the body having a pocket open at its face, a condiment carrier, a supporting member for the carrier, and means at the forward face of the rail pivotally supporting the member whereby the carrier may be swung between a position in the pocket and a position adjacent a side of the body. 10
6. In a cooking range having a body and a cover hinged to the body to be swingable to an upwardly projecting open position adjacent the rear side of the body, the combination of, a guard rail projecting upwardly from the body along the upper rear corner of the body and having a forwardly facing opening that is inaccessible when the cover is raised, a shiftable condiment carrier, and means supporting the carrier for movement from an accessible position in the opening to a position beyond the vertical plane occupied by the cover to be accessible when the cover is opened. 15
7. In a cooking range a range body, a rear guard rail on the body, the rail having a pocket open at its face, a carrier for holding receptacles or the like, and means supporting the carrier for movement between a position in the pocket where the receptacles are accessible at the face 20
8. In a cooking range having a rear guard rail having a pocket open at its face and a cover hinged to be raised to a substantially vertical position in front of the rail, the combination of, a carrier for holding receptacles or the like, means supporting the carrier for movement between a position in the pocket where the receptacles are accessible at the face of the rail and a position beyond an end of the range where the receptacles are accessible when the cover is in a substantially vertical position, and stop means limiting movement of the carrier in said positions. 25
9. A cooking range comprising a range body, a condiment carrier including, a plurality of rods shaped to form the ends and sides of the carrier, at least one of the rods being extended horizontally to project from the carrier, bottom members connected to the rods to form the bottom of the carrier, said ends, sides and bottom defining an open topped pocket for receiving condiment receptacles, and means supporting the carrier for movement between a position adjacent the upper rear extremity of the body and a position adjacent an end of the body, said means including a bearing on the body pivotally carrying said projecting rod. 30

ROBERT J. MERRITT. 35
